UNITED STATES PATENT OFFICE.

JOSEPH CAUGHEY, OF MILDURA, VICTORIA, AUSTRALIA.

MEANS FOR WINDING, TIGHTENING, STRAINING, AND THE LIKE.

1,264,011.

Specification of Letters Patent. Patented Apr. 23, 1918.

Application filed October 25, 1917. Serial No. 198,467.

To all whom it may concern:

Be it known that I, JOSEPH CAUGHEY, a subject of the King of Great Britain and Ireland, &c., residing at Mildura, in the 5 State of Victoria, Commonwealth of Australia, have invented certain new and useful Improvements in Means for Winding, Tightening, Straining, and the like; and I do hereby declare the following to be a full, 10 clear, and exact description of the invention, such as will enable others skilled in the art to which it appertains to make and use the same.

My invention relates to improved means 15 for winding, tightening, straining, and the like, the operation being performed by the use of a reel or core and by a rotator thereof aided by a plug and one or more locking members, the latter being means for (after 20 rotation) fixing the reel or core against unwinding relatively to any clothes line, cord, wire, rope, chain, or article operated upon. The article to be wound, tightened, or strained will, for brevity, be hereinafter 25 called the wire; the article on which it is wound will, for brevity, be called the reel; and straining and pulling as well as winding operations will, for brevity, be indicated by the word winding.

30 In drawings herewith, in which the scales differ, embodiments of my invention are illustrated, but there may be modifications while retaining matter which is hereinafter covered in my claims.

35 In practice the parts shown as vertical in the drawings might take or be given some other position, as horizontal.

Figure 1 shows a side view of a reel.

Fig. 2 shows a front view of a rotator 40 with parts omitted.

Fig. 3 shows part of the said rotator with the reel mounted on it. Fig. 4 shows part of the rotator seen at right angles to its position in Fig. 2.

45 Fig. 5 shows the reel in middle section, with a wire, a rotator, and a plug, in the positions assumed prior to rotation.

Fig. 6 shows the parts in Fig. 5 in positions assumed after slight rotation, and with 50 a locking member inserted to prevent unwinding.

Fig. 7 is a plan of the parts in Fig. 5.

Fig. 8 is a plan of parts in Fig. 6 but with the reel slightly retracted from the position 55 of the latter figure.

A is a wire, B a reel, C a plug, usually of

tapered or wedge form, but it may be of any suitable size and shape. D is a rotator, shown with forked handles D¹, a stem D², a pointer or nose D³, which is shown tapered and a bearing surface D⁴ made for example by cutting a recess in the nose. It may have at the end of the recess a stop D⁵ for a reel, and it may have means as holes D⁶ for the use if required of a member to prevent detachment of the reel during rotation.

The reel has any suitable flanges or cheeks B¹, a barrel or axle B², a central hole B³ through the barrel, and an aperture or slot B⁴ in the barrel wall. This slot allows of 70 location and gripping of the wire before winding. The dimensions of slot B⁴ are variable and it is shown wider in Fig. 8 than in other figures; the arc through which it extends may also vary. The cheeks are provided, as around their rims, with a series of holes or the like B⁵ in such positions that holes of opposite cheeks will retain in position locking pieces, which may be plain, or, as shown at E corrugated or the like, to 75 make it less easy for them to be pushed out of the holes when in use. Corrugations are marked E¹, but a screw, a common nail, or a piece of straight wire has been found to serve. But for greater security, any projecting end as E² or ends of the locking member may be bent, as seen in Fig. 8.

In operating the invention the reel will be set against the wire as in Fig. 5 and the nose D³ of the rotator will be inserted in 90 the center hole B³ its bearing surface D⁴ contacting with the wire, and its outer surface with the barrel, and the wedge shaped plug C will also be inserted in the hole, the nose and the plug gripping the wire firmly 95 between them and being themselves held sufficiently tightly in the barrel.

The rotation is then effected, and in many cases there will be no danger of the reel slipping off the nose; but when desired such 100 slip is guarded against by a stop, for example a pin or the like in a hole D⁶ the pin end or ends projecting therefrom, this pin being movable to allow the rotator to be detached.

The direction of rotation shown by an arrow in Fig. 6 applies to the wire therein, but the rotator could have been turned the opposite way. In practice there will be usually greater winding than is illustrated. 110

The number of holes B⁵ (or equivalents as slots) may be varied.

According to the dimensions of the reel and the extent of rotation, so will more or less wire be wound on between the cheeks or flanges B¹. When the winding is sufficient a locking piece or pieces is or are inserted in holes B⁴ as in Fig. 8 or secured in place by means of the cheeks. If only one locking piece be used it would allow the reel to retract somewhat more than if two locking pieces were used, the extent of retraction being small if holes B⁴, are spaced closely. Then the rotator can be extracted from center hole B⁵, and the tapered plug or the like will remain firmly in the reel.

15 When unwinding of material like stiff wire is desired it can be effected by inserting and using the rotator; the plug can be disengaged from the reel at will to free the wire.

20 To prevent loss of loose plugs, locking pieces, and (or) the nose pin or the like, they may be connected at will, as by links or chains, to the parts which carry them.

Having described this invention, what is 25 claimed by Letters Patent is:—

1. In combination, a reel having a hollow hub and side flanges, the hollow hub having a transverse slot which communicates with the hollow portion of said hub, a rotator extending through the hollow hub and provided with a cutaway portion which registers with the transverse slot, a plug inserted through the hollow hub and spaced

from the rotator to form a clamp for a wire when passed through the transverse slot, whereby when the rotator and reel are turned the opposite ends of the wire will be drawn taut.

2. In combination, a reel having a hollow hub and a transverse slot, a plug fitted in the hollow hub and spaced from the inner wall thereof, a wedge shaped plug extending through the hollow hub and spaced from the plug to form a clamp for a wire extending through the slot, whereby when the reel 45 is rotated the opposite ends of the wire will be drawn taut, and pins extending across the reel to engage the wire to prevent reverse movement of the reel.

3. In combination, a reel having a hollow hub, and a transverse slot, a plug fitted in the slot, a plug fitted in the hollow hub and spaced from the inner wall thereof, a wedge extending through the hollow hub and spaced from the plug to form a clamp 55 for a wire extending through the slot, whereby when the reel is rotated the opposite ends of the wire will be drawn taut, and corrugated pins extending through the reel, the wire on opposite sides of the hub 60 engaging in the corrugations in the pins to prevent reverse movement of the reel.

In witness whereof I have hereunto set my hand.

JOSEPH CAUGHEY.
